UNITED STATES PATENT OFFICE

JOHN L. ERISMAN, OF CHICAGO, ILLINOIS, ASSIGNOR TO H. W. CALDWELL & SON COMPANY, OF CHICAGO, ILLINOIS, A CORPORATION OF ILLINOIS

SCREW CONVEYER

Application filed October 9, 1924. Serial No. 742,548.

My invention relates to improvements in screw conveyers. It has for one object to provide a new and improved type of screw conveyer which will result in a minimum destruction of bearings and which will increase the capacity of the device.

Experience shows that there is a tendency for the material in the trough to pile up at the bearing points where the screw is interrupted to permit room for the bearing, and I propose, therefore, to provide means for increasing the capacity of the conveyer at the bearing point so as to prevent this piling up and thereby prevent wear of the bearing.

What happens is that in the normal operation the screw moves the material along to the trough in a steady stream. At the points where the screw is interrupted to make a place for the bearing, the material piles up until the pile is high enough so that the material fed to the pile will run down by gravity across the gap to the point where the flight on the next section of screw can get at it. This pile is frequently higher than the bearing, and therefore the bearing is exposed to direct contact with the piled up material.

I propose to terminate each bearing section with a double screw element, thus increasing the capacity of the screw at that point and providing means for projecting the material across the gap and keeping the pile of material down.

In general, my device comprises in one form a hollow screw shaft with the spiral flight wound about. There is a manganese stub shaft between the ends of each such power shaft and flight, and this manganese shaft rotates in the bearing. Associated with this manganese stub shaft are two collars. These collars preferably overlie part of the bearing sleeve and each collar has one or more spiral paddles or segmental flights thereon, there being but a single paddle on the hollow shaft. These two flights may or may not

have different angles of inclination from the balance of the screw, and they can be arranged to project the material across the gap without difficulty and therefore carry the material continuously and protect the bearing.

The invention is illustrated more or less diagrammatically in the accompanying drawings, wherein—

Figure 1 is a perspective view of the conveyer screw in its assembled position;

Figure 2 is a similar view showing the arrangement partially disassembled;

Figure 3 is an end elevation of one of the end flights;

Figure 4 is a section along the line 4—4 of Fig. 3.

Figure 5 is a side elevation of a bearing.

Like parts are indicated by like characters throughout the specification and drawings.

In the drawings I have omitted the trough and its associated parts, because they form no part of the present invention and would add nothing to the clearness of the device.

A is a supporting bracket which may be mounted on the trough or near the suitable supporting or anchoring means. This supporting bracket contains a two-part or split bearing sleeve A¹. This bearing sleeve has an inner cylindrical bearing surface to engage the stub end shaft A². The opposed ends of the sleeve A¹ are reduced as at A³. A⁴ is a hollow shaft mounted on the stub shaft A²; it carries a spiral conveyer flight or screw A⁵ wound about its periphery in the usual manner, this flight terminating at each end of the shaft A⁴.

B is an end flight sleeve cupped to surround the reduced portion of the sleeve A³, and adapted to be keyed or otherwise fastened on the stub shaft A², and will abut snugly against the shaft A⁴. On this end flight sleeve are a plurality of segmental end flight paddles or screws B¹, B². These end flight screws are of substantially the same

diameter as the screws A⁵ and extend toward the ends of the shaft clear up until adjacent to the plane of the end of the end flight sleeve B. Thus they somewhat overhang the actual bearing surface in which the stub shaft is carried.

I have not illustrated means for driving the shaft or means for feeding material to the trough, as this forms, also, no part of my invention.

When the device is in operation, the entire series of separate hollow shafts are rotated in unison; material fed to the trough at any point is carried forward along the bottom of the trough by the spiral action of the members A⁵, and as the material reaches the point at which the single spiral terminates it is caught by the end flight paddles or screws and thrown across the gap occasioned by the bearing, until it is caught by the end flight screws on the other side of the bearing and delivered by them to the normal spiral.

It will be evident that while I have shown in my drawings an operative device, still many changes might be made in the size, shape and arrangement of parts without departing from the spirit of my invention. I wish, therefore, that my drawings be regarded as in a sense diagrammatic.

While I have referred to the shaft as being hollow, it might, of course, be solid. I have also referred to the stub shaft as made of manganese and while for some purposes this is preferable, many other materials might be used. In the figures, I show on each of the collars two flights. One only might be used or more than two might be used.

I claim:

1. In a screw conveyer, a plurality of separate screw sections, bearings interposed between them, means associated therewith for conveying material across the gap occasioned by the bearing, said means comprising a plurality of segmental screw paddles arranged adjacent the bearing, the angle of inclination of said paddles being different from the angle of inclination of the spiral on the shaft.

2. In a screw conveyer, a plurality of separate screw sections, a bearing interposed between them and means associated therewith for conveying material across the gap occasioned by the bearing and for protecting the bearing, said means comprising a plurality of cup-shaped members, each adapted to engage one of the screw sections and to over-hang the bearing, and each carrying a plurality of segmental screw paddles arranged adjacent the bearing.

3. In a screw conveyer, a plurality of separate screw sections, a bearing interposed between them and means associated therewith for conveying material across the gap occasioned by the bearing and for protecting the bearing, said means comprising a plurality of cup-shaped members, each adapted to en-

gage one of the screw sections and to overhang the bearing, and each carrying a plurality of segmental screw paddles arranged adjacent the bearing, the angle of inclination of said paddles being different from the angle of inclination of the screw portion on the shaft.

Signed at Chicago, county of Cook and State of Illinois, this 2nd day of October, 1924.

JOHN L. ERISMAN.
